UNITED STATES PATENT OFFICE.

RUDOLPH LIEBMANN, OF NEW YORK, N. Y.

DESIGN FOR A BUTTON.

41,808.

Specification for Design. Patented Sept. 26, 1911.

Application filed June 25, 1910. Serial No. 568,941. Term of patent 3½ years.

To all whom it may concern:

Be it known that I, RUDOLPH LIEBMANN, a citizen of the United States, residing at New York city, borough of Manhattan, in the State of New York, have invented a new, original, and ornamental Design for Buttons, of which the following is a specification, reference being had to the accompanying drawing, forming part thereof.

Figure 1 is a face view of a button, showing my new design, and Fig. 2 is an edge view of the same.

As shown in said drawing, my new design consists in displaying at the front of a round

button a single elliptical stone or imitation thereof which extends diametrically across the face of the button and arranging in the crescent-shaped spaces at each side of said elliptical stone series of small stones or imitations thereof separated from each other by spaces on the face of the button.

I claim:

The ornamental design for a button or similar article, as shown and described.

RUDOLPH LIEBMANN.
